UNITED STATES PATENT OFFICE.

JAMES P. HERRON, OF WASHINGTON, DISTRICT OF COLUMBIA.

DEVICE FOR PRESERVING POSTAGE-STAMPS.

Specification forming part of Letters Patent No. 39,147, dated July 7, 1863.

To all whom it may concern:

Be it known that I, JAMES P. HERRON, of the city and county of Washington, and District of Columbia, United States of America, have invented a new and useful Method of Preserving Postage or Letter and other Stamps, &c., from Cohesion; and I do hereby declare the following to be a full and exact description thereof, reference being had to the accompanying drawings, and to the letters of reference marked thereon, making a part of this specification, in which—

Figure 1 is a surface view of a section of stamps and tin-foil, or other prepared metallic substance, one-half the size of the section of the stamps, the blue surface *e f c d* exhibiting tin-foil or other metal, &c. Fig. 2 is a representation of the folding of a package of stamps, the blue line exhibiting the tin-foil and the black line the stamps.

I take a sheet or section of postage or other stamps, Fig. 1, *a b c d*, and a piece of tin or any metallic sheet smoothed with oil, or its equivalent, to prevent adhesion, one-half the

size of the postage or other stamps, Fig. 1, *e f c d*, placing the metallic or tin foil on the gummed surface of the stamps, folding them so as to have the metallic substance between the gummed surface only, Fig. 2, as exhibited by the blue line, thus preventing the stamps from all injurious adhesion, &c.

Knowing that tin-foil has been used for packing and securing drugs, groceries, &c., from dampness, and the injurious action of the atmosphere, &c., I do not claim to secure stamps from dampness or atmospheric action on them; but

What I claim as new and useful, and desire to secure by Letters Patent, is—

To preserve postage-stamps, &c., after being damp or wet, from adhering and drying together, or to surfaces injuring them or rendering them useless, as specified and set forth.

JAMES P. HERRON.
